UNITED STATES PATENT OFFICE

151,434

DESIGN FOR A TOY FIGURE

Kenneth R. Eames, Worcester, Mass.

Application March 11, 1947, Serial No. 137,517

Term of patent 14 years

(Cl. D34—15)

To all whom it may concern:

Be it known that I, Kenneth R. Eames, a citizen of the United States, residing at Worcester, in the county of Worcester and State of Massachusetts, have invented a new, original, and ornamental Design for a Toy Figure, of which the following is a specification, reference being had to the accompanying drawing, forming part thereof.

Fig. 1 is a perspective view of a toy figure, showing my new design;

Fig. 2 is a left hand side elevation thereof;

Fig. 3 is a partial longitudinal sectional elevation;

Fig. 4 is an enlarged front view of the head; and

Fig. 5 is an enlarged side elevation of the head.

I claim:

The ornamental design for a toy figure, as shown.

KENNETH R. EAMES.
